UNITED STATES PATENT OFFICE.

RICHARD W. UHLIG, OF NEW YORK, N. Y., ASSIGNOR TO WILLIAM B. BALDWIN, OF SAME PLACE.

TYPE-WRITING MACHINE.

SPECIFICATION forming part of Letters Patent No. 625,616, dated May 23, 1899.

Application filed December 29, 1896. Serial No. 617,364. (No model.)

To all whom it may concern:

Be it known that I, RICHARD W. UHLIG, a resident of New York, (College Point,) in the county of Queens and State of New York, have 5 invented certain new and useful Improvements in Type-Writing Machines; and I do hereby declare the following to be a full, clear, and exact description of the invention, such as will enable others skilled in the art to which 10 it appertains to make and use the same.

My invention relates to an improvement in type-writing machines, and more particularly to improvements on the carriage and devices carried thereby, one object of the invention 15 being to provide simple and efficient paper carrying and feeding mechanism.

A further object is to construct the carriage of a type-writing machine in such manner that a portion of the carriage can be easily 20 raised to permit the last line of writing to be readily seen by the operator.

With these objects in view the invention consists in certain novel features of construction and combinations and arrangements of 25 parts, as hereinafter set forth, and pointed out in the claims.

In the accompanying drawings, Figure 1 is a perspective view with a part of the guard broken away. Fig. 2 is a cross-section. Figs. 30 3 and 4 are end views. Fig. 5 is an elevation with the hinged portion of the carriage raised. Figs. 6 and 6^a are detail views. Fig. 7 is a view of a modification.

My improvements are intended more particularly for use on type-writing machines of 35 the "type-wheel" class.

My improved carriage comprises two parts A B, the part A being constructed to slide on the frame of the machine and is provided with 40 a ratchet-bar 1 to be engaged by the ratchet feed mechanism. (Not shown.) The part A of the carriage is provided at its ends in line with the rear edge with perforated lugs 2 2 for the accommodation of a rod 3, which latter 45 also passes through end plates 4 5 of the part B, whereby to hinge the latter to the part A, and thus permit the part B to be raised to facilitate the reading of the last line of writing, the paper carrying and feed mechanism being 50 mounted on the said hinged part B of the carriage.

A rubber-covered feed-roller 6 is mounted between the plates 4 5 of part B of the carriage, one of the journals of said roller being extended beyond its bearing for the reception 55 of a knob 7. A smaller feed-roller 8 is disposed at one side of the roller 6, and its journals 9 are mounted in elongated slots or bearings 10 in the end plates 4 5. A paper carrying or retaining roller 11, preferably of wood and of 60 greater diameter than either feed-roller, is disposed at the other side or in rear of the feed-roller 6 and is provided with journals 12, mounted in elongated slots or bearings 13 in the end plates. The rollers 8 and 11 are yield- 65 ingly impelled toward the feed-roller 6 by means of springs 14, located at the respective ends of the carriage and connecting the journals of said rollers 8 and 11. In order to facilitate the turning of the paper-supply roller 70 11 when the paper is being wound thereon, one of the journals of said roller is provided with a knob 15. A bar 16 is located between the feed-rollers and secured at its ends to the end plates 4 5. This bar serves to support a 75 guide 17, which can be conveniently made of a single piece of sheet metal so bent as to cause one edge to be disposed in close proximity to the smaller feed-roller 8 and its other edge to be disposed between the rollers 6 and 11 and 80 partially embrace the former.

From this construction it will be seen that when the end of a sheet of paper is placed between the feed-rollers and the roller 6 turned by means of the knob 7 the paper 85 will be drawn between said feed-rollers, and as the turning of the roller 6 is continued the paper will be directed partially around it by the guide 17 and will thus be delivered to the supply-roller 11. The paper will be guided 90 around the roller 11 (which latter may now be turned by the knob 15) by means of a series of spring-fingers 18, supported by a rod 19, mounted in slots 19^a in the end plates 4 5 of part B of the carriage. (See Fig. 2.) Instead of the spring-metal fingers 18 rubber 95 bands 20 (see Fig. 7) may be used for causing the paper to properly wind on the roller 11, in which case the rubber bands will be supported by rods 21, mounted between the 100 end plates 4 5.

The journal of the feed-roller 6, which is

- mounted in the end plate 4, is extended beyond the outer face of said plate and provided at its extremity with a ratchet-wheel 23. A lever 24 (approximately L-shaped and having both arms curved) is loosely mounted on said journal of the roller 6. The lower arm *a* of lever 24 is made with a socket *b* for the reception of a small coiled spring *c*, and the wall of said socket is made with a small socket *d* for the reception of one end of said coiled spring. The bottom of the spring-socket *b* is screw-threaded for the reception of the screw-threaded end of a pin *e*, by means of which a dog *f* is pivotally connected with the arm *a* of lever 24. The pivoted end of the dog *f* is also made with a socket *g* for the reception of the coiled spring *c* and also with a small socket *h* for the reception of the end of said spring. From this construction it will be seen that the spring *c* tends to force the free end of the dog into engagement with the ratchet-wheel 23; but it is desirable that the dog be held normally out of engagement with the ratchet-wheel, so that the feed-roller 6 can be readily and freely turned during the act of inserting or removing a sheet of paper into or out of the machine without the annoyance of the clicking sound caused by the dog riding over the teeth of the ratchet-wheel.
- In order to maintain the dog normally out of engagement with the ratchet-wheel, the dog is provided with an inner cam-face *i*, which will be engaged by a pin *j* on the plate 4, so as to move the dog away from the ratchet-wheel, when the lever 24 returns to its normal position by means of a spring 25, one end of which is attached to the arm *b* of said lever and the other end to a pin projecting from the plate 4. The lever 24 is prevented from being pulled too far by the spring 25 by means of the engagement of a tooth *k* on the arm *b* of said lever with a pin or stop *l* on the plate 4. The pin *l* also serves as a guide for a slotted bar 26, said bar being also guided by another pin 27 and is provided at its upper end with a thumb-piece 28, by means of which it can be readily depressed. The lower end of the bar 26 is cut away, as at 29, so as to permit the engagement of the tooth *k* with the pin *l*. From this construction it will be seen that when the bar 26 is depressed by the operator its lower end will engage the arm *b* of lever 24 and turn said lever on its fulcrum, thus moving the dog *f* away from the pin *j*, so as to permit it to engage the ratchet-wheel and rotate the same and the feed-roller 6, the movement of the lever 24 being limited by the engagement of a shoulder 37 thereon with the sliding bar 26.
- When the slotted bar 26 is depressed, motion will be imparted, as above explained, to the feed-roller 6. The end of the paper wound on the paper-supply roller will project upwardly between the rollers 6 and 8, so as to be held by the pressure of said rollers toward each other, and thus when the roller 6 is rotated motion will be imparted to the roller 8

in the opposite direction, and the two rollers will act to draw the paper from the roller 11, so as to cause it to be fed upwardly and permit it to pass over the paper-guard C. My improvements are designed more particularly for use with a type-writing machine of the "wheel" class, and hence the paper as it passes upwardly from the feed-rollers will be disposed between the type-wheel and hammer of the machine. The extent of feed of the paper when the bar 26 is depressed is limited for double lines by engagement of a pin 30 on said bar with the lower end of slot 31 in the end plate 4.

In order to provide means whereby the paper can be fed a single line at each depression of the bar 26, I provide a pivoted arm 32, having a shoulder 33, which can be disposed in the path of the pin 30, and thus limit the downward movement of the bar 26. The pivoted arm 32 is made with an elongated opening 34, through which a rod 35 of the carriage passes and serves to limit the movements of said pivoted arm.

The usual paper-guard C is attached to a rod 36 of the carriage.

The reason for hinging the upper part of the carriage is not to permit access to the paper for erasing, &c., as in "bar" machines, but merely to allow the operator to more readily see the last line of writing. It is therefore only necessary that the upper portion of the carriage have a slight movement, and the extent of this movement will be limited by means of a stop 38. The stop 38 is made in the form of an arm attached to one part of the carriage and having shoulders 40 and 41 to engage a pin 42 on the other part of the carriage. When the shoulder 40 is in engagement with the pin 42, the two parts of the carriage will be locked together; but when it is desired to view the last line of writing the stop-arm 38 may be moved slightly, (limited by a pin 43,) so as to disengage it from the pin 42, and then the upper part of the carriage can be raised, its upward movement being limited by the engagement of the shoulder 41 with the pin 42. The stop-arm 38 will be constantly impelled toward the pin 42 by means of a weight 44, projecting at an angle from the pivoted end of said arm 38.

My improvements are simple in construction and effectual in all respects in the performance of their functions.

Slight changes might be made in the details of construction of my invention without departing from the spirit thereof or limiting its scope, and hence I do not wish to limit myself to the precise details herein set forth.

Having fully described my invention, what I claim as new, and desire to secure by Letters Patent, is—

1. In a carriage for type-writing machines, the combination with a base sliding frame, of a frame carrying all the paper carrying and feeding devices and hinged at its rear edge to the base-frame so as to be raised bodily

- therefrom on its hinged connection with said base-frame, a latch pivoted to the base-frame and having two shoulders and a pin on the upper frame to be engaged by said shoulders.
5. 2. In a carriage for type-writing machines, the combination with a base sliding frame, of an upper frame mounted upon and hinged at one edge to the base-frame, paper carrying and feeding devices mounted in the upper frame, a weighted latch pivoted to the base-frame and having two shoulders and a pin to be engaged by said shoulders, projecting from the upper frame, substantially as set forth.
3. The combination with a carriage comprising a lower sliding part and a part hinged to the sliding part, of a paper-carrying roller adapted to have a supply of paper wound thereon and feed-rollers mounted in the hinged part of the carriage and paper-guides
- 15 20 also carried by the hinged part of the carriage and constructed and adapted to guide the paper to and cause it to be wound on the paper-carrying roller, substantially as set forth.
- 25 4. The combination with the carriage of a type-writing machine, of a paper-carrying roller mounted in the carriage and adapted to have sheets of paper wound thereon, feed-rollers also mounted in the carriage and co-
- 30 35 operating with the paper-carrying roller and curved fingers constructed to embrace and hug the paper-carrying roller so as to insure the proper and accurate winding of the sheets of paper thereon and the unwinding of the sheets of paper therefrom, substantially as set forth.
5. In a type-writing machine, the combination with a carriage, of two feed-rollers and a paper-carrying roller mounted by the side of
- 40 45 one of said feed-rollers, said carrying-roller and one of the feed-rollers being mounted in elongated bearings in the end plates of the carriage, and springs at each end of the carriage, one arm of each spring being attached to the journal of the paper-carrying roller and the other end of each spring being attached to the journal of the feed-roller mounted in elongated bearings, substantially as and for the purpose set forth.
- 50 55 6. In a type-writing machine, the combination with a carriage, of two paper-feed rollers and a paper-carrying roller, a bar secured to the carriage and a guide supported by said bar, said guide being adapted to direct the paper partially around one of the feed-rollers and deliver it to the carrying-roller, substantially as set forth.
7. In a type-writing machine, the combination with a carriage, of two feed-rollers and
- 60 65 a paper-carrying roller, of a guide secured to the carriage, one edge of said guide being dis-
- posed in proximity to one of said rollers and the other part of the guide partially embracing the other feed-roller and terminating at its edge in proximity to the paper-carrying roller, substantially as set forth. 65
8. In a type-writing machine the combination with a carriage and a feed-roller, of a lever pivotally supported between its ends on a journal of said feed-roller, a spring-actuated dog carried by one end of said lever, a pin on the carriage to engage and normally maintain said dog out of engagement with the ratchet-wheel but permitting it to engage said ratchet-wheel when the lever is turned in one direction, and a vertically-movable push-bar mounted on the carriage adapted to engage the other end of said lever, substantially as set forth. 70 75
9. In a type-writing machine, the combination with a carriage and a feed-roller, of a ratchet-wheel secured to the feed-roller, a pivoted lever, a socket in one end of said lever, a dog having a socket therein, a spring disposed in said sockets and having its ends 80 85 attached respectively, to the lever and dog, means for maintaining the lever and dog in their normal positions and means for operating said lever, substantially as set forth. 85
10. In a type-writing machine, the combination with a carriage and a feed-roller mounted therein, of a pivoted lever, a ratchet-wheel secured to the journal of the feed-roller, a dog carried by said lever to engage the ratchet-wheel, a spring attached at one end to said 90 95 lever and at the other end to the carriage whereby to maintain the lever and dog in their normal positions, a sliding bar to engage said lever and stops to limit the movements of said lever, substantially as set forth. 100
11. In a type-writing machine, the combination with a carriage and a feed-roller mounted therein, of a ratchet-wheel secured to the journal of said roller, a pivoted lever, a dog carried by said pivoted lever and adapted to 105 engage the ratchet-wheel, a spring attached at one end to said lever and at the other end to the carriage, a stop for said lever, a sliding bar having a thumb-piece, said bar being adapted to engage said lever, a pin for limiting the downward movement of said sliding bar, and a pivoted arm having a shoulder to be moved into the path of said pin whereby to limit the downward movement of said sliding bar, substantially as set forth. 110 115

In testimony whereof I have signed this specification in the presence of two subscribing witnesses.
